[57] CLAIM

The ornamental design for a lamp, as shown and described.

DESCRIPTION

FIG. 1 is a top plan view of the lamp showing my new design.

FIG. 2 is a bottom plan view of the lamp of FIG. 1; and, FIG. 3 is an enlarged front elevation view of the lamp of FIG. 1, the rear being identical to the front except for the position of the base.

The side view of the lamp of FIG. 1 is identical to FIG. 3 for every 120 degrees of rotation of the lamp from FIG. 3. Features shown in broken lines are shown for environment only and do not form a part of the design claimed.
